UNITED STATES PATENT OFFICE.

MATTHEW C. CAMPBELL, OF PHILADELPHIA, PENNSYLVANIA.

TRAMWAY AND CAR.

SPECIFICATION forming part of Letters Patent No. 309,689, dated December 23, 1884.

Application filed June 19, 1884. (No model.)

To all whom it may concern:

Be it known that I, MATTHEW C. CAMPBELL, a citizen of the United States, residing at Philadelphia, in the county of Philadelphia and State of Pennsylvania, have invented certain new and useful Improvements in Tramways and Cars, of which the following is a specification, reference being had therein to the accompanying drawings, wherein—

10 Figure 1 is a perspective of a tramway and car with station appurtenances embodying my invention. Fig. 2 is a side elevation of the car or carriage drawn to an enlarged scale, and Fig. 3 is a sectional view of bumper mechanism located at one of the stations or termini of the tramway.

15 My invention has relation to tramways of that form composed of oppositely-inclined tracks over which a car is propelled back-

20 ward and forward between two stations or termini; and it has for its object to adapt the same for pleasure purposes at seaside or other resorts, as well as making them practically useful for conveying goods or material of any kind, by so constructing the tramway, car, and one of the stations that the momentum or velocity and the gravity of the car can be utilized to propel it in addition to the motive power with which it is supplied, thereby effecting a saving in the amount of said motive power required for moving the car to and fro upon the tramway.

25 My invention accordingly consists of the combination, construction, and arrangement 35 of parts, as hereinafter described and claimed, having reference to a tramway composed of a series of inclines having end stations or termini, a car provided with hand or other motive-power mechanism, a bumping arrangement or device at one of the tramway-stations, and to stations, one of which has egress and ingress openings for the passengers, and the other is devoid of such openings.

30 In the drawings, A represents the bed of the tramway or tracks $a a$, and which may be upon the ground or elevated above it by means of suitable supports, as shown, or which may be of any desired construction and arrangement. The tracks $a a$ are laid so as to have a

posed or made up of wave-like inclinations or grades b^2 , b^3 , and b^4 , of varying pitch, so that the pitch of the grades $b' b'$ will not be uniform from the portion b to the stations or terminal points C C'. The station or terminus C is provided with egress and ingress openings or passages c for the incoming and outgoing passengers, and when the tramway is elevated above the ground said station is furnished with stairways D, as shown; or a wide or other inclined gangway may be substituted for the stairway. The station C' is devoid of entrances and exits for passengers, but is provided with a bumping device, F, firmly bolted 55 or secured thereto at f or other suitable point in line of the travel of the car G. This bumper F is more plainly shown in Fig. 3, and consists of a casing, g, having a plunger, g', with bumping-head g^2 , and spiral spring or cushion 70 g^3 , for receiving and absorbing the shocks of bumping, and to react upon and give the car its initial return movement after entering station C'.

75 The car or carriage G may be of any suitable construction and design. I have shown it in the form of a gondola or boat having a cover or roof, G', hand or other motive power mechanism, H, and bumping ends or heads I.

80 The operation is obvious. The car is propelled or travels to and fro over the varying grades of the tramway or between its stations, being moved or propelled by hand-power applied to the crank h; but in passing down one grade or inclination the gravity of the car 85 gives it a momentum, and the velocity acquired by the car as it descends a grade is utilized to assist moving it up a succeeding or ascending grade, so that less power is required for rotating the crank h to operate the 90 mechanism H to effect the movement of the car to and from the stations C and C'. The car, as it passes into the station C', or when it arrives at the end of one-half of its journey, strikes against the bumper-head g^2 to compress spring g^3 , the reaction of which assists in giving the car its initial return movement. It is obvious, therefore, that the car can be propelled to and fro between the stations C and C' by the use of a minimum of hand or other power commensurate with the load required 100 to be moved.

The different grades of the inclinations b b' may be of any desired or suitable length and degree of pitch. I have found that a length of forty-five feet for grades b b' b^4 and a pitch 5 or inclination varying from eighteen inches to four and a half feet therefor gives excellent results; but different proportions and inclinations for the same may be used with good effects. These grades not only effect a saving 10 of power requisite for moving the car, but also give to the latter a rolling or undulating motion as it travels to and fro upon the tramway.

Instead of using hand-power mechanism for propelling the car G, any other suitable power 15 mechanism may be substituted—as, for instance, a spring, compressed-air engine, or other well-known means.

I have shown and described my invention as being mainly adapted for pleasure purposes, 20 or for carrying passengers over the tramway; but it is evident that it can be used for moving freight or other material from one point or location to another. So, too, if desired, a circular segmental or other appropriate form 25 of tramway may be substituted for the straight one shown, and any suitable form of brake mechanism may be applied to the car. I however prefer one so arranged that it can be 30 operated by the foot of the attendant propelling the car.

What I claim is—

1. A tramway composed of descending and ascending grades or tracks, each of which is made up of a series of varying grades, in combination with a car provided with motive-power mechanism, substantially as shown and described. 35

2. A tramway having end stations, one of which is provided with a bumping device, in combination with a car having hand or power mechanism, substantially as shown and described. 40

3. A tramway composed of tracks of varying grades or inclinations, in combination with end stations, one of which has a bumping device, and a car provided with power appliances or driving mechanism, substantially as shown and described. 45

4. The combination of station C, having entrances and exits, the station C, devoid of such entrances and exits, the connecting tramway or tracks a a' , and car G, having driving mechanism H, substantially as shown and described. 50

In testimony whereof I affix my signature in presence of two witnesses.

MATTHEW C. CAMPBELL.
